UNITED STATES PATENT OFFICE.

PATRICK H. ROBINSON, OF RACINE, WISCONSIN, ASSIGNOR TO HAMILTON BEACH MFG. CO., OF RACINE, WISCONSIN, A CORPORATION OF WISCONSIN.

VACUUM-CLEANER-NOZZLE ADJUSTMENT.

Application filed September 24, 1926. Serial No. 137,477.

This invention relates to improvements in vacuum cleaner nozzle adjustments.

In using a vacuum cleaner on rugs and carpets in which the length of the nap differs, the relation of the proximity of the nozzle to the rug surface changes according to the length of the nap.

It is, therefore, the primary object of the present invention to provide a vacuum cleaner in which the nozzle may be adjusted in relation to the surface being traveled over.

A further object of the invention is to provide an easily manipulated manual adjustment for vacuum cleaner nozzles.

15 A further object of the invention is to provide a nozzle adjustment for vacuum cleaners adaptable to any form of vacuum cleaner.

20 A further object of the invention is to provide a vacuum cleaner nozzle adjustment which is of very simple construction, is inexpensive to manufacture, is strong and durable, and is well adapted for the purpose described.

25 With the above and other objects in view, the invention consists of the improved vacuum cleaner nozzle adjustment, and its parts and combinations as set forth in the claims, and all equivalents thereof.

30 In the accompanying drawing in which the same reference characters indicate the same parts in all of the views:

Fig. 1 is a plan view of the suction nozzle of a vacuum cleaner, parts being broken away and in section to show details of construction;

Fig. 2 is a side view of the suction nozzle; and

Fig. 3 is a fragmentary sectional view showing the relation of the brush to the opening of the nozzle mouth, and on a larger scale.

Referring now more particularly to the drawing, it will appear that the numeral 5 indicates the motor housing portion of a vacuum cleaner from the forward end portion of which depends a suction nozzle 6 having an open lower mouth portion 7. The rear end portion of the motor housing is supported by a suitably mounted wheel 8.

A U-shaped lever member 9 is arranged to have the portion intermediate the arms 10 extend externally along the rear of the suction nozzle and closely adjacent thereto, and the parallel arm members 10 extend inward-

ly into the nozzle housing through slots cut through the rear wall of the nozzle and through the rearwardly extending lugs 6' near each side of the nozzle at the rear. The lever 9 is pivotally secured to the nozzle housing by the pins 11 extending through said lugs 6' and through the lever arms 10, near the point where the arm 10 joins the rear member of the lever 9. Revolvably secured to the inner end portions of the arms 10 of the lever 9 by means of studs 11' are wheels 12 for supporting the suction nozzle 6 in proper relation to the surface to be cleaned. The lever member 9 has secured thereto an upstanding arm 13 having a curved-free end portion 14.

Adjacent the arm 13, the suction nozzle is provided with a lug portion 15 having a threaded stud 16 extended thereinto. A knob member 17 is revolvably mounted on the end portion of the stud 16 and the knob is formed with an enlarged bore portion 18 to receive the head of the stud 16 and a coiled spring 19. Mounted on the stud 16 inwardly of the knob member 17 is an eccentric or cam member 20 on the edge of which the free end portion 14 of the arm 13 is adapted to ride. The cam member 20 is connected to the knob member 17 by means of a lug 21 extending laterally from the knob member and a pin 22 passed through the cam member and said lug. By this means, the cam member will turn on the stud with the knob member when the latter is turned. A collar 23 is interposed between the cam member and the lug portion 15 of the nozzle to correctly space the cam member.

In order to hold the arm 13 firmly in engagement with the cam member 20, a flat spring 24 is provided which is secured at one end to the arm member, and which yieldingly engages at its free end, the suction nozzle 6, as clearly shown in Fig. 2.

By the construction described the major portion of the lever 9 is exterior of the nozzle and closely in rear thereof, and the arms 10 of the lever 9 carrying the wheels 12 are interior of the nozzle housing, but separated from the suction chamber by the supplemental walls 25; and the adjusting mechanism is conveniently located exteriorly of the nozzle housing, for actuating the lever 9. The location of the arms 10 and wheels 12 within the nozzle housing is a great advantage in preventing damage to furniture.

and to the wheels, without interfering with the desirable exterior connection between the adjusting means and the lever 9.

The improved nozzle adjusting means described is, of course, adapted to move the forward wheels 12 and the mouth of the nozzle with respect to each other to vary the distance of the mouth from the surface to be cleaned, depending on the character of said surface. To accomplish adjustments, the hand knob 17 is turned, causing the arm 13 to ride on raised or depressed portions of the cam member 20. This movement of the arm will accordingly move the U-lever 9 and cause the lower portion of the vacuum cleaner to pivot at its inner end on the wheel 8 to raise and lower the mouth portion of the suction nozzle.

From the foregoing description, it will be seen that the improved vacuum cleaner nozzle adjustment is of very simple and novel construction, and is well adapted for the purpose set forth.

What is claimed as the invention is:

1. The combination with the body of a vacuum cleaner including a forward suction nozzle, of a floor engaging support pivotally carried by the rear end portion of said body, a lever pivotally secured to said suction nozzle, forward supporting wheels carried by said lever, a cam member rotatably mounted on said body adjacent said lever externally of the suction nozzle, an arm projecting from said lever and adapted to ride externally on said cam member, and means permitting manual turning of said cam member to move said arm and lever.

2. The combination with a body of a vacuum cleaner including a forward suction nozzle, of a floor engaging support pivotally carried by the rear end portion of said body, a lever pivotally secured to said suction nozzle, forward supporting wheels carried by said lever, a cam member rotatably mounted on said body adjacent said lever externally of the suction nozzle, an arm secured to and projecting from said lever and adapted to ride externally on said cam member, and a knob secured to said cam member for turning the same to move said arm and lever to adjust the height of said suction nozzle mouth from the floor.

3. The combination with the body of a vacuum cleaner including a forward suction nozzle, of a floor engaging wheel pivotally carried by the rear portion of the body, a U-shaped lever extending longitudinally of the suction nozzle and pivotally secured thereto, forward supporting wheels journaled in the end portions of said lever, a cam member rotatably mounted on said body adjacent said lever and externally of the suction nozzle, an arm rigidly secured at its lower end portion to the lever and projecting upwardly therefrom and adapted to ride ex-

ternally on said cam member, resilient means carried by said arm and engaging the body to hold said arm in engagement with said cam member, and a knob secured to said cam member for turning the same to move said arm and lever to adjust the height of said suction nozzle mouth from the floor.

4. A vacuum cleaner including a housing, a suction nozzle, a floor engaging support pivotally carried by the rear portion of the housing, a U-shaped lever having forwardly extending parallel arms, the lever portion intermediate said arms being located externally of and closely in rear of the suction nozzle, the rear wall of the suction nozzle being slotted to receive the parallel arms of the lever, wheels rotatably carried by said parallel arms near their forward ends and located within the nozzle, the lever arms being pivotally connected to the nozzle, and adjusting means secured to the nozzle, externally thereof and intermediate the lever arms, for actuating the lever and for maintaining it in any one of a plurality of positions.

5. A vacuum cleaner including a housing, a suction nozzle, a floor engaging support pivotally carried by the rear portion of the housing, a U-shaped lever having forwardly extending parallel arms, the lever portion intermediate said arms being located externally of and closely in rear of the suction nozzle, the rear wall of the suction nozzle being slotted to receive the parallel arms of the lever, wheels rotatably carried by said parallel arms near their forward ends and located within the nozzle, the lever arms being pivotally connected to the housing rearwardly of the wheel connections, and adjusting means secured to the nozzle, externally thereof, and intermediate the lever arms, for actuating the lever and for maintaining it in any one of a plurality of positions.

6. A vacuum cleaner including a housing, a suction nozzle, a floor engaging support pivotally carried by the rear portion of the housing, a U-shaped lever having forwardly extending parallel arms, the lever portion intermediate said arms being located externally of and closely in rear of the suction nozzle, the rear wall of the suction nozzle being slotted to receive the parallel arms of the lever, wheels rotatably carried by said parallel arms near their forward ends and located within the nozzle, the lever arms being pivotally connected to the nozzle, and adjusting means secured to the nozzle, externally thereof and intermediate the lever arms, for actuating the lever and for maintaining it in any one of a plurality of positions, said means including a cam fixedly secured to the nozzle, a knob for actuating the cam and an arm secured to the lever and in engagement with the cam.

In testimony whereof, I affix my signature.
PATRICK H. ROBINSON.
